UNITED STATES PATENT OFFICE.

GEORGE C. DEVITT, OF BUFFALO, NEW YORK, ASSIGNOR TO BUFFALO SCALE COMPANY,
OF BUFFALO, NEW YORK, A CORPORATION OF NEW YORK.

PIVOT FASTENING FOR SCALE LEVERS.

Application filed March 2, 1922. Serial No. 540,615.

To all whom it may concern:

Be it known that I, GEORGE C. DEVITT, a citizen of the United States, residing at Buffalo, in the county of Erie and State of New York, have invented new and useful Improvements in Pivot Fastenings for Scale Levers, of which the following is a specification.

This invention relates to scales and more particularly to that type of scales in which levers are employed having pivot pins forming parts of the pivotal connections between the same and other members of the scale.

In scales of this character as heretofore constructed, the pivots have been secured to the levers by casting the latter thereon, or the same were made separate and secured thereto by fastening means which were of complicated, expensive and unreliable construction.

It is the object of this invention to provide means for fastening the pivot pins to the levers of a scale by means which are simple, durable, reliable and capable of being readily manipulated for exchanging the pivot pins when renewal of the same becomes necessary due to wear.

In the accompanying drawings: Figure 1 is a fragmentary vertical longitudinal section of a platform scale having its various levers provided with pivot pins which are fastened thereto in accordance with my invention. Figure 2 is a horizontal section taken on line 2—2, Fig. 1. Figure 3 is a fragmentary side elevation, on an enlarged scale, of the center pivotal connection between the long lever and the short lever. Figure 4 is a fragmentary vertical longitudinal section, on an enlarged scale, of the center connection taken on line 4—4, Fig. 5. Figure 5 is a cross section taken on line 5—5, Fig. 3. Figures 6 and 7 are vertical sections, on an enlarged scale, taken on lines 6—6 and 7—7, Fig. 1, respectively. Figures 8, 9 and 10 are perspective views of the yoke, pivot pin and lever forming parts of one form of my invention. Figure 11 is a fragmentary vertical longitudinal section, showing a modified form of my invention.

Similar characters of reference indicate corresponding parts throughout the several views.

In its general construction, the scale shown in Figs. 1 and 2 of the drawings, comprises a hollow base or frame 12, a hollow

column or pillar 13 rising from one end of the base adjacent to a corner thereof, a bifurcated short lever 14 arranged lengthwise in the base and pivotally mounted thereon, a bifurcated long lever 15 also arranged with in the base and pivotally connected with the same and the short lever, a platform 16 arranged above the opening in the base and provided with downwardly projecting legs or brackets 17 which are pivotally mounted on the short and long levers, and a steel yard rod 18 arranged vertically within the column and pivotally connected at its lower end with the free end of the long lever while its upper end is connected with the scale beam in the usual or any approved manner.

The foregoing parts comprise the main elements of an ordinary platform scale which are adapted to be connected by means which embody my invention but it is to be understood that my invention is also applicable to other forms of scales.

The several pivotal connections between the short and long levers themselves and between these levers and other members of the scale are constructed as follows:

20 represents main bearing pivot pins arranged on the scale levers and each having a downwardly tapering V-shaped front face or knife edge 21 and a rounded back face 22, and 23 represents horizontal supporting pins mounted on the base immediately above the lever pins 20. 24 represents base or frame shackles or hangers each of which is pivoted at its upper end on one of the supporting pins 23 and is provided on its lower part with a bearing 25 upon which the lower knife edge of a lever pivot pin rests, as shown in Figs. 1, 2 and 7. Each of the pivot pins 20 is detachably connected with the adjacent scale lever as follows:

26 represents a notch, preferably V-shaped, arranged transversely on the upper horizontal side and forming a seat which is engaged by the lower knife edge of one of the pivot pins 20. This pin is held in engagement with the respective lever by a yoke of U-form the upright legs 27 of which straddle a part of this lever while the cross piece or bar 28 of the same extends across that side of the lever opposite to that containing the pivot pin notch.

The free ends of the legs of the yoke are provided with openings 29 which receive the respective pin 20 adjacent to opposite verti-

cal sides of the lever and are adapted to bear against the rounded back side or face of the pivot pin. Means are provided for moving the yoke vertically in a direction away from the notch of the lever, so that the pivot pin is firmly clamped against its seat therein and will not become displaced while in use but still permit this pin to be removed from the lever and replaced by another when this becomes necessary owing to wear or other reasons.

In the form shown in Figs. 1 and 7, the yoke of each main bearing pivot pin 20 is moved in a clamping or tightening direction by means of a clamping screw 30 which works in a threaded opening in the cross piece or bar of the respective yoke and engages with the adjacent horizontal surface of the respective lever. By this means the pivot pin can be very quickly tightened or loosened on the lever when assembling or dismembering the parts and permit of keeping the scale in a sensitive and accurate condition.

31 represents the platform pivot pins of the pivotal connections between the platform legs 17 and the levers. In this case the pivot pins 31 have their knife edges projecting upwardly and engaging with V-shaped notches 32 in the underside of the levers and the platform legs 17 are suspended from these pins by shackles 34 connected at their lower ends by pins 35 with the legs 17 while their upper parts are provided with bearings 36 engaging with the knife edges of these pivot pins. Each of the pivot pins 31 is detachably held in engagement with the seat on the respective lever by a U-shaped yoke, the legs 37 of which are arranged vertically and straddle the lever and are provided with openings 38 which receive the pivot pin 31 on opposite sides of the lever and a cross piece 39,—which has a threaded opening which receives a clamping screw 40 pressing against the side of the lever opposite to the notch 32 therein.

41, 42 represent the upper and lower pivot pins of the center connection, the upper pivot pin having its knife edge turned upwardly and engaging its opposite ends with V-shaped seats 43 on the underside of the upper or long lever 15, while the lower pivot pin 42 has its knife edge turned downwardly and engaged at its opposite ends with V-shaped seats 44 on the upper side of the lower or short lever. The two center connection pivots are connected with each other by a shackle 45 which is provided with upper and lower bearings 46, 47 engaging with the knife edges of the upper and lower center connection pins between the ends of the same. Each end of the lower center pin 42 is detachably connected with the adjacent part of the short lever by a U-shaped yoke having vertical legs 48 pro-

vided with openings 49 which receive the lower pin 42 and a cross bar 50 which receives a screw 51 pressing against the underside of the short lever, the construction and operation of this clamping device being the same as that employed in connection with the main bearing pins 20. The upper center pin 41 is clamped at each end against the upper long lever by a U-shaped yoke having vertical legs 52 which straddle the long lever and have openings 53 receiving the respective pivot pin 41 and a cross bar or piece 54 arranged over the upper lever opposite the notch 43 therein. In order to tighten each of the upper center connection yokes, a wedge 55 is driven between the upper side of the long lever and the under side of the cross bar of the respective upper center yoke, as shown in Figs. 1, 2, 3, 4, and 5, thereby holding the parts in place relatively to each other without the use of screws as in the before mentioned yokes.

56 represents the steelyard pivot pin mounted on the free end of the long lever and having its downwardly turned knife edge engaged by a bearing arranged on a shackle or link 57 similar to the hereinbefore described shackles and connected with the lower end of the steelyard. This steelyard pivot is detachably clamped on the free end of the long lever in the same manner in which this is done with reference to the lower center pivot pin 42 on the short lever and the same characters of reference are therefore employed to designate corresponding parts.

Instead of using either a screw or a wedge to tighten the yoke on the pivot pin and hold the latter in place on a scale lever, this may be accomplished by providing the cross piece or bar 58 of the U-shaped yoke with two lips 59 on its transverse edges which are bent inwardly against one horizontal side of the scale lever 60 and thereby draw the knife edge of the pivot pin 61 carried by the legs 62 of this yoke against the correspondingly shaped seat 63 on the opposite side of this lever, as shown in Fig. 11.

Each of the several forms of fastening permit of quickly and securely attaching the pivot pin to the yoke lever instead of casting the lever on the pivot pin.

I claim as my invention:

1. A scale lever provided with a seat, a pivot pin engaging said seat, and means for fastening said pivot to said scale lever comprising a U-shaped yoke the legs of which straddle said scale lever and are provided with openings for receiving the pivot pin on opposite sides of the lever and the cross piece of which is arranged on that side of said lever opposite to its seat.

2. A scale lever provided with a seat, a pivot pin engaging said seat, and means for fastening said pivot to said scale lever com-

- prising a **U**-shaped yoke the legs of which straddle said scale lever and are provided with openings for receiving the pivot pin on opposite sides of the lever and the cross piece of which is arranged on that side of said lever opposite to its seat, and clamping means which operate to draw said clip in a direction for pressing said pivot pin against said seat.
10. 3. A scale lever provided with a seat, a pivot pin engaging said seat, and means for fastening said pivot to said scale lever comprising a **U**-shaped yoke the legs of which straddle said scale lever and are provided with openings for receiving the pivot pin on opposite sides of the lever and the cross piece of which is arranged on that side of said lever opposite to its seat, and a clamping screw working in said cross piece and engaging said lever on that side opposite its seat.
4. A scale lever provided with a transverse notch which is **V**-shaped in form, in a plane lengthwise of the lever, a pivot pin arranged parallel with said notch and having a **V**-shaped bearing face engaging with said notch, and a **U**-shaped yoke having its legs straddling said lever and its cross piece extending over that side of the lever opposite to the notch therein, said legs being provided with openings which receive said pivot pin on opposite sides of the lever and bear against the rounded sides of said pin, and a clamping screw working in a threaded opening in said cross piece and engaging with that side of the lever opposite to the notch thereon.
5. A scale lever provided with a transverse notch which is **V**-shaped in form, in a plane lengthwise of the lever, a pivot pin arranged parallel with said notch and hav-
- ing a **V**-shaped bearing face engaging with said notch and a rounded back on that side thereof opposite to its **V**-shaped face, and a **U**-shaped yoke having its legs straddling said lever and its cross piece extending over that side of the lever opposite to the notch therein, said legs being provided with openings which receive said pivot pin on opposite sides of the lever and bear against the rounded sides of said pin.
6. A scale lever provided with a transverse notch which is **V**-shaped in form, in a plane lengthwise of the lever, a pivot pin arranged parallel with said notch and having a **V**-shaped bearing face engaging with said notch and a rounded back on that side thereof opposite to its **V**-shaped face, a **U**-shaped yoke having its legs straddling said lever and its cross piece extending over that side of the lever opposite to the notch therein, said legs being provided with openings which receive said pivot pin on opposite sides of the lever and bear against the rounded sides of said pin, and a clamping screw working in a threaded opening in said cross piece and engaging with that side of the lever opposite to the notch thereon.
7. A scale lever provided on one of its horizontal sides with a notch forming a seat, a pivot pin engaged on one of its sides with said seat, and means passing around the opposite side of said pivot pin and around the opposite side of said lever for fastening said pivot pin to said lever.

GEORGE C. DEVITT.
